UNITED STATES PATENT OFFICE

130,608

DESIGN FOR A PRESSER FOOT FOR SEWING MACHINES

Samuel B. Bilger, Lancaster, Pa.

Application August 25, 1941, Serial No. 103,013

Term of patent 14 years

To all whom it may concern:

Be it known that I, Samuel B. Bilger, a citizen of the United States, residing at Lancaster, in the county of Lancaster and State of Pennsylvania, have invented a new, original, and ornamental Design for a Presser Foot for Sewing Machines, of which the following is a specification, reference being had to the accompanying drawing, forming part thereof.

The figure is a perspective view of a presser foot for sewing machines illustrating my new design.

I claim:

The ornamental design for a presser foot for sewing machines, as shown.

SAMUEL B. BILGER.
